UNITED STATES PATENT OFFICE.

HARRY K. CLEMONS, OF ST. PAUL, MINNESOTA, ASSIGNOR TO WHEELING CORRUGATING COMPANY, OF WHEELING WEST VIRGINIA, A CORPORATION OF WEST VIRGINIA.

TUBE-CONTRACTOR FOR RIVETING-MACHINES.

1,277,862.

Specification of Letters Patent.

Patented Sept. 3, 1918.

Application filed January 4, 1917. Serial No. 140,625.

To all whom it may concern:

Be it known that I, HARRY K. CLEMONS, a citizen of the United States, residing at St. Paul, in the county of Ramsey and State of Minnesota, have invented certain new and useful Improvements in Tube-Contractors for Riveting-Machines; and I do hereby declare the following to be a full, clear, and exact description of the invention, such as will enable others skilled in the art to which it appertains to make and use the same.

My invention relates to punch and riveting machines, and especially to those used for punching and riveting corrugated sheet metal culverts, and provides, as an attachment thereto, a simple and efficient device for contracting the ends of the telescoped culvert sections while at least the first connecting rivet is being applied thereto.

These corrugated sheet metal culverts, as now in very general use, are made with overlapped longitudinal seams connected by rivets and the sections are connected together by telescoping the corrugated ends. This telescoping of the ends of the culvert sections necessitates leaving out at least some of the rivets immediately adjacent to the ends to be telescoped. Practice has shown that where the tubes are thus telescoped and then punched and riveted, it is necessary to hold the same contracted by some suitable contracting device while at least the first punch is being made and the first connecting rivet applied. My invention is directed primarily to an improved tube contracting device for the above purpose.

In the accompanying drawings which illustrate the invention, like characters indicate like parts throughout the several views.

Referring to the drawings:

Figure 1 is a side elevation showing a punching and riveting machine and my improved tube contracting device applied for use in connection therewith;

Fig. 2 is a front elevation of the parts shown in Fig. 1;

Fig. 3 is a detail view in front elevation showing parts of the cable tightening drum and ratchet mechanism; and

Fig. 4 is a fragmentary view in plan of certain of the parts shown in Fig. 3.

Of the parts of the combined punch and riveter, it is only necessary for the purposes

of this case to particularly note the heavy frame 5, the long horizontally projecting anvil or horn 6 and the vertically movable press head 7. This press head 7 will be given vertical movements in the customary way through mechanism, not shown, but which is operated from a driving pulley 8 and coöperating shaft 9, under the control of the usual lever mechanism 10, 11, 12, 13 and 14. This feature, however, constitutes no part of the present invention.

The press head 7 carries the usual punch 15 and hammer 16 which coöperate, respectively, with a punch die 17 and anvil block 18 on the projected end of the horn 6.

Loosely mounted on the projecting front end of the driving shaft 9 is a windlass drum 19 that has a ratchet flange 20. Keyed to the shaft 9 and working within the laterally projecting flange of the windlass drum 19 is a disk-like clutch shoe carrier 21 to which clutch shoes 22 are pivoted. These shoes 22 are connected by oblique or toggle-acting links 23 to a shipper hub 24 that is rotatable with but slidable on the said shaft 9.

The numeral 25 indicates a bearing frame that is rigidly secured to the end of the main frame 5 adjacent to the vertically movable press head 7 and is provided with depending portions in which is mounted a horizontal slide 26 having at one end a stripper arm 27 adapted to be moved to and from engagement with the culvert section or tube, and when in operative position, serving to hold down the tube and strip the same from the upwardly moving punch.

The numeral 28 indicates a shipper lever pivoted at one end to a lug on the bearing frame 25 and having pins 29 that engage an annular groove in the shipper hub 24.

The numeral 30 indicates a windlass latch lever pivoted to a projection of the bearing frame 25 and having a lock or retaining dog 31 that is normally engageable with the latch flange 20 of the windlass drum 19.

The clutch mechanism and windlass drum described, are arranged to operate the compressed cable of a floating or traveling windlass, preferably constructed as follows:

32 indicates an overhead track supported in any suitable way, and 33 indicates a small weighted truck or traveler mounted to run on the lower flanges of the rail 32. A bar

34 is intermediately supported from the frame of the truck 33, as shown, by a short chain 35, and to one end of this bar is pivotally connected the upper end of a long upright floating column 36. This so-called floating column is preferably made up of a pair of laterally spaced bars, between the lower ends of which is rigidly but adjustably secured a laterally projecting anchor 37. The adjustment between the anchor 37 and the lower ends of the bars of the column 36 is shown as made by pins 38 and coöperating perforations 39.

The free end of the bar 34 is adjustably connected to the intermediate portion of the column 36 by means of a truss bar 40, the lower end of which, as shown, is perforated and arranged to be adjustably connected by a pin 41 to a metal strip or bracket 42 on the said column. By adjustments of the truss bar 40, the lower end of the floating column, and hence the anchor 37, may be adjusted. A contracting cable 43 is detachably connected at one end to the anchor 37, by means of a hook 44, or the like, and the other end of this cable is attached to the windlass drum 19, by means of a staple 45, or the like. This cable 43 is passed over guide sheaves 46, 47 and 48 on the column 36 and bar 34.

The corrugated sheet metal culvert sections are indicated by the character *a* and their longitudinal seams are indicated by the character *a'*. Of the culvert sections shown in Fig. 1, that at the left is the pivotally riveted section and may be connected to others farther at the left, but the culvert section at the right is in the process of completion and may be assumed to have its joint *a'* connected only by one rivet located about two corrugations from its right hand end. At its left hand end, the said right hand culvert section has its joint *a'* loose, but is telescoped over the right hand end of the left hand culvert section and is ready for connection thereto by the application of a rivet applied at the overlapped end portions of the two culvert sections. Before this is done, however, the said left hand end of the right hand culvert section should be contracted tightly against the right hand end of the left hand culvert section and this is accomplished as follows:

The lower end of the contracting cable 43 is passed around the left hand end of the said right hand culvert section, say at the third corrugation thereof, and is attached to the anchor 37. Then by manipulation of the lever 28, the friction clutch is set and the windlass drum 19 will be rotated until the proper contraction of the tube or culvert section is accomplished, and then the clutch is, of course, released. The retaining dog 31 will automatically lock the cable under this set tension. Then the hole is first punched

through the overlapped ends of the two culvert sections at the joint of the outer thereof; next, a rivet is applied through this punched hole; and then the rivet is upset between the hammer 16 and anvil block 18. After this has been done, the tension on the contracting cable is released by raising the lever 30, and the lower end of the cable may be detached from the anchor 37 and the derrick moved toward the right, or otherwise, to a position out of the way, while the punch and riveter is used to complete the riveting of the longitudinal joint of the last or right hand section and the circumferential joint between the telescoped ends of the two sections.

The windlass drum is desirable because there may be considerable slack in the cable and because it must have sufficient length to adapt itself to culvert sections or tubes of very greatly different diameters. However, from the broader point of view, this so-called windlass drum is an oscillating clutch actuating cable take-up device or tightener.

What I claim is:

1. A machine for contracting culvert sections, and the like, comprising a cable, an anchor for holding one end of said cable while it is wrapped around the culvert section, and a driven clutch actuated cable take-up device applied to the other end of said cable.

2. A machine for contracting culvert sections, and the like, comprising a cable, an anchor for holding one end of said cable while it is wrapped around the culvert section, a power-driven clutch actuated cable take-up device applied to the other end of said cable, and a pawl and ratchet device releasable, at will, but automatically operated to hold said cable under its set tension.

3. A machine for contracting culvert sections, and the like, comprising a cable, a floating derrick frame having guides for said cable and an anchor for the lower end thereof, and a clutch actuated power-driven cable take-up device applied to the other end of said cable.

4. A machine for contracting culvert sections, and the like, comprising a cable, a floating derrick frame having guides for said cable and an anchor for the lower end thereof, a clutch actuated power-driven cable take-up device applied to the other end of said cable, and a pawl and ratchet device releasable at will but operative automatically to lock said cable under its set tension.

5. The combination with a riveting machine having an anvil, of a tube contracting device operated from one of the running parts of said riveting machine and arranged to contract a tube positioned on said anvil.

6. The combination with a power-driven riveting machine having an anvil, of a clutch controlled tube contracting device operated

from one of the running parts of said riveting machine and arranged to contract a tube positioned on said anvil.

7. The combination with a power-driven riveting machine having an anvil, of a clutch controlled tube contracting device operated from one of the running parts of said riveting machine and comprising a cable adapted to be wound around a tube positioned on

said anvil and to be put under tension 10 through the controller of said clutch.

In testimony whereof I affix my signature in presence of two witnesses.

HARRY K. CLEMONS.
